FOREIGN PATENT DOCUMENTS

CN 305003650 * 1/2019

Primary Examiner — Paula Allen Greene

(57) **CLAIM**

The ornamental design for a ear phone, as shown and described.

DESCRIPTION

FIG. 1 is a front elevational view of an ear phone showing my new design;

FIG. 2 is a back elevational view of the ear phone;

FIG. 3 is a front view of the ear phone;

FIG. 4 is a back view of the ear phone;

FIG. 5 is a top view of the ear phone;

FIG. 6 is a bottom view of the ear phone; and,

FIG. 7 is a perspective view of the ear phone.
